US00D661373S

(12) **United States Design Patent**
Moodycliffe et al.

(10) **Patent No.:** US D661,373 S
(45) **Date of Patent:** ** Jun. 5, 2012

(54) **CAROUSEL FOR A FLUID DISPENSING DEVICE**

(75) Inventors: **Timothy I. Moodycliffe**, Milwaukee, WI (US); **Daniel R. Nett**, Sun Prairie, WI (US); **Craig P. Conner**, Madison, WI (US); **Mark W. Cors**, Columbus, WI (US); **Mark D. Duennes**, Wheeling, IL (US); **Douglas A. Soller**, Racine, WI (US); **Cory J. Nelson**, Racine, WI (US); **Jose M. Arevalo**, Racine, WI (US)

(73) Assignee: **S.C. Johnson & Son, Inc.**, Racine, WI (US)

(**) Term: **14 Years**

(21) Appl. No.: **29/400,665**

(22) Filed: **Aug. 31, 2011**

CLAIM

The ornamental design for a carousel for a fluid dispensing device, as shown and described.

DESCRIPTION

FIG. 1 is an isometric view of a carousel for a fluid dispensing device of the present invention;

FIG. 2 is a front elevation view of the carousel of FIG. 1; FIG. 3 is a left side elevation view of the carousel of FIG. 1; FIG. 4 is an elevation view from the left and front of the carousel of FIG. 1; and,

FIG. 5 is another elevation view from the left and front of the carousel of FIG. 1.

The broken lines represent environmental structure and form no part of the claimed design.

1 Claim, 5 Drawing Sheets
